[57] ABSTRACT

Certain pyrazines have been found to be useful as detergent builders in laundry formulations. Exemplary is 1,4,5,6-tetrahydro-5,6-dioxo-2,3-pyrazinedicarbonitrile.

9 Claims, No Drawings

PYRAZINE COMPOUNDS

BACKGROUND OF THE INVENTION

1. Field of the Invention

This invention relates to the use of certain pyrazines as detergent builders, to detergent compositions containing such pyrazines, and to certain useful metal salts of said pyrazines.

2. Description of the Prior Art

Certain pyrazines have been reported in the literature, as for example 1,4,5,6-tetrahydro-5,6-dioxo-2,3-pyrazinedicarbonitrile [Bredereck & Schmötzer, Ann. 600, 95-108 (1956)]; pyrazinetetracarboxylic acid and its dipotassium salt [Chattaway & Humphrey, J. Chem. Soc. 1929, 645]; pyrazine-2,6-dicarboxylic acid, its calcium salt and several other of its metal salts [Stoehr & Detert, J. prakt. Chem. 55, 248 (1897); and Mager & Behrends, Rec. trav. chim. 77, 827 (1958)]. Permanganate oxidation of 2,3-dichloroquinoxaline to 5,6-dihydroxypyrazine-2,3-dicarboxylic acid is described by Mager & Behrends, Rec. trav. chim. 77, 842 (1958) [Chem. Abs. 53, 10241 (1959)] and the acid is disclosed to form a compound containing four silver atoms when reacted with silver nitrate. A precursor, 2,3-dihydroxyquinoxaline (regarded to be a tautomeric form of 2,3-diketotetrahydroquinoxaline) is indicated to form insoluble compounds with Ca, Sr, and Ba ions. Matthews and Walton, Inor. Chem. 10, No. 7, 1433 (1971) disclose insoluble pyrazine carboxylate complexes with metals such as silver, copper, cobalt and nickel. Non of these prior art materials have been disclosed as possible components of detergent compositions.

DESCRIPTION OF THE INVENTION

It has now been found that certain pyrazines, their esters, and certain of their water soluble salts are effective complexing agents for calcium and magnesium.

They have the ability of being able to complex calcium and magnesium in neutral to basic (pH 7-12) aqueous solutions wherein the complex itself remains in at least metastable solutions. This property makes the pyrazine compounds useful as builders in detergent compositions, as for example, replacements for sodium tripolyphosphate. The pyrazine compounds have also been found to have surfactant properties, particularly those where R³ in the formula below has eight or more carbon atoms.

One aspect of the invention comprises a detergent composition containing a surfactant and a pyrazine compound selected from the group consisting of

a. a compound of the formula

wherein R¹ and R², alike or different, are CN or COOR³ in which R³ is H, alkyl, oxaalkyl, (alkylphenyl)oxaalkyl, of 1-48 carbon atoms; and water soluble salts thereof; and

b. 2,6-pyrazinedicarboxylic acid, pyrazinetetracarboxylic acid, 3,5-bis(methoxycarbonyl)-2,6-pyrazine-dicarboxylic acid, and 3,6-bis (methoxy-

carbonyl)-2,5-pyrazinedicarboxylic acid, and water soluble salts thereof; the said pyrazine compound being present in an amount effective to chelate calcium ions in a basic medium.

A detergent composition is defined as a material which has a cleansing action like soap but is not directly derived from fats and oils. Such a composition generally contains synthetic detergents and may also contain soaps if desired. Synthetic detergents are surface active agents containing both hydrophilic and hydrophobic groups. Three types are generally recognized. (1) Anionic detergents which have negatively charged ions attached to the oil-soluble portion of the molecule and examples are sodium salts of organic sulfonates or sulfates such as alkylaryl sulfonates, e.g., sulfonates of dodecylbenzene. (2) Cationic detergents which ionize so that the oil-soluble portion is positively charged as for example quaternary ammonium halides. (3) Nonionic detergents which do not ionize but acquire hydrophilic character from a polar segment, such as polyoxyethylene.

The synthetics are usually used in combination with other active ingredients such as polyphosphates, polysilicates, sodium carboxymethylcellulose, sodium hydroxide and sodium carbonate, and with inert diluents such as sodium sulfate and water. A typical heavy-duty detergent might consist of 20% organic surfactant, 45% phosphate detergent builders, 25% sodium sulfate, silicates, other inorganic builders, 10% miscellaneous, including perfumes, optical brighteners, soil-suspending agents and moisture.

The pyrazine is present in an amount effective to complex calcium and/or magnesium at a pH range of 7 to 12 and the resulting complex in water soluble at such pH range. The complex is water soluble when formed but may gradually become insoluble. The amount of the pyrazine in the detergent composition can vary over a wide range. A preferred range is 10 to 45% of the pyrazine compound by weight based on the total weight of the detergent composition. A more preferred range is 15-35%.

Certain of the above monoester and diester pyrazines appear to be new compounds of the formula:

wherein R⁴ and R⁵, alike or different, are selected from the group OH, alkoxy, oxaalkoxy, (alkylphenyl)oxaalkoxy each of 1-48 carbon atoms, and, together, are -O-, with the proviso that only one of R⁴ and R⁵ is OH; and with the further proviso that when R⁴ and R⁵ are alkoxy groups, each alkoxy group contains 4-48 carbon atoms; and watersoluble salts thereof.

The new esters are easily prepared. The lower diesters, that is, where R⁴ and R⁵ contain up to 3 carbon atoms, are obtained by conventional esterification procedures, e.g., by reacting 1,4,5,6-tetrahydro-5,6-dioxo-2,3-pyrazinedicarboxylic acid, its monosodium or mon ammonium salt, with a lower alcohol under acidic reaction conditions. Mixed diesters are produced when mixed alcohols are used. To obtain monoesters or diesters

ters of alcohols containing four or more carbon atoms, 1,4,5,6-tetrahydro-5,6-dioxo-2,3-pyrazinedicarboxylic anhydride is heated with the desired alcohol. Simple heating of the anhydride and alcohol produces the monoester; further heating in the presence of an excess of the alcohol and an acid esterification catalyst, e.g. HCl, HBr, H₂SO₄, and p-toluenesulfonic acid, etc., produces the diester. A mixed diester is prepared when mixed alcohols are used. The alcohols correspond to the formulas HR⁴ and HR⁵ where R⁴ and R⁵ are as previously defined with the proviso that they are not OH, since water, when reacted with the anhydride will not produce an ester.

Salts of 5,6-dihydroxy-2,3-pyrazinedicarbonitrile, the enol form of 1,4,5,6-tetrahydro-5,6-dioxo-2,3-pyrazinedicarbonitrile, can be readily prepared. The water-soluble alkali metal salts, i.e., the lithium, sodium and potassium salts, are useful as detergent builders.

SPECIFIC EMBODIMENTS OF THE INVENTION

In the following illustrative examples all parts are by weight and temperatures are in degrees Centigrade unless otherwise stated.

EXAMPLE 1

A. Calcium Chelating Activity by preventing of calcium carbonate precipitation

The calcium chelating activity (CCA) of a compound is roughly determined by an alkaline titration process⁽¹⁾ as follows: A dry 2-g sample of the compound is dissolved in 50 ml of water and the pH of the solution is determined.

(1) Hampshire NTA and Its Salts, A Bulletin on Nitritotriacetic Acid and its Sodium Salts; Hampshire Chemical Corporation, Nashua, New Hampshire

If the solution is below pH 7, sufficient 1 N sodium hydroxide is added to bring it to the neutral point. Aqueous sodium carbonate (2%, 10 ml) is added, and the pH of the solution is adjusted to 11.5 with additional sodium hydroxide. The solution is then diluted to a volume of 100 ml and titrated within 1 to 2 minutes with aqueous calcium acetate (44.1 g monohydrate per liter, equivalent to 25 mg CaCO₃ per ml) to a distinct and

permanent turbidity. If desired, a different amount of the candidate compound can be used and the amounts of other materials adjusted in proportion according to the above recipe. The CCA is expressed in terms of milligrams of CaCO₃ chelated per gram of compound, calculated as follows:

$$CCA = \frac{(ml \text{ Ca acetate}) \times 25}{wt \text{ of sample}}$$

Table IA presents the results of the test described in Part A above on known detergent builders and on various pyrazines. Pyrazine compounds capable of chelating calcium, by the aforesaid alkaline titration procedure, to the extent of at least 75 mg of CaCO₃ per gram of pyrazine, are preferred. More preferred are those compounds which chelate at least 200 mg of CaCO₃.

The dioxo compounds No. 10 and No. 11 in Table IA below form water soluble calcium complexes in the presence of carbonate at pH 7-12. This can be attributed to their ability to form stable enolate anions in basic solutions as evidenced by changes in their infrared absorption spectra under certain conditions. The tautomerism can be illustrated by the equation

30 The pure compounds are indicated to be predominantly in the dioxo form since they show high carbonyl absorption and none attributable to hydroxyl or aromatic double bonds in the infrared. In basic environment, however, they are indicated to shift into the pyrazinolate form since they then show no carbonyl absorption and strong absorption in the aromatic double bond regions. In the usual basis (sodium salt) detergent compositions, these builders are most likely present as the di- and trisodium salts.

^(*)"Carbitol" is 2-(2-ethoxyethoxy)ethanol

^(**)"Carbowax-350" is a mixture of (polyoxa)alkanols (monomethyl ether of polyoxethylene) corresponding to the average formula $\text{CH}_3(\text{OCH}_2\text{CH}_2)_{7.2}\text{OH}$.

^(***)Titrated dilute solution with calcium acetate to point where all suds were destroyed.

^(****)"Ipegal-530" is 18-(nonylphenyl)-3,6,9,12,15,18-hexaoxaoctadecan-1-ol.

^(*****)"Alfol-1216" is a mixture of (polyoxa)alkanols [mono(long chain alkyl) ether of polyoxethylene] corresponding to the average formula $\text{CH}_3(\text{CH}_2)_{12}-(\text{OCH}_2\text{CH}_2)_{4.8}\text{OH}$.

(1) Calculated on anhydrous basis, if a hydrate. CCA values greater than 1000 probably do not represent stoichiometric complexes.

(2) Sample not soluble to the extent of 2% at pH 11.5 and could not be tested by this method.

B. Calcium Chelating Activity by Calcium Ion Selective Electrode

The calcium chelating activity of a compound may be measured by using a calcium selective electrode to de-

termine the amount of unchelated calcium ion. A suitable instrument is Calcium Electrode Model 9220 sold by Orion Research, Inc. The procedure used is as follows: a buffered solution was prepared containing

0.03M ammonium chloride, 0.07M ammonium hydroxide and 2×10^{-3} M calcium carbonate (200 ppm CaCO_3) with pH 9.5. To 250 ml of this solution was added enough test compound so that the same number of moles of compound were present as moles of calcium carbonate. The potential of the calcium ion selective electrode was recorded and compared with a calibration curve to determine the amount of unchelated calcium ion and by difference the amount of chelated calcium ion.

Table IB presents the data for two pyrazines and two known detergent builders. These data are probably more meaningful than the data in Table IA. For example, several compounds in Table IA had apparent CCA above 5,000. Such high CCA values are unlikely for they imply one chelant molecule may complex five or more calcium ions. Indeed compound No. 6 which shows CCA above 5,000 by a method A shows only CCA 104 by Method B.

TABLE II

Compound	"Clorox" (ml/g of cmpd)	CCA

EXAMPLE 2

Effect of Bleaching Agents on Chelating Activities

A. "Clorox"

The following data show the effect on calcium chelating activities of adding "Clorox" to the mixtures in the test procedure of Example 1. "Clorox" is an aqueous solution containing 5.25% sodium hypochlorite.

B. Various Bleaching Agents

60 The effect of each bleaching agent was determined by adding an excess of the bleaching agent to 10 ml of a stock solution (0.13% by volume) of the sodium salt of 1,4,5,6-tetrahydro-5,6-dioxo-2,3-pyrazinedicarbonitrile. After a short time, a 1-ml sample of the mixture was diluted to 100 ml and its ultraviolet absorbance measured immediately and again after 5 days. The following table presents the data obtained.

TABLE III

Bleach	Amount	Absorbance at 325 nm	
		15-30 min	5 Days
None		0.96	
		1.01	
Percarbonate	0.050 g	0.97	0.23
Perborate	0.053 g	0.94	0.35
30% H ₂ O ₂	0.1 ml	0.94	0.72
'Beads O' Bleach" ¹¹	0.050 g	0.98	0.99
'Clorox"	0.5 ml	0.13	0.15
'Clorox"	0.38 ml	0.29	0.28
'Clorox"	0.12 ml	0.70	0.68

¹¹"Beads O' Bleach" did not give a clear solution in the stock solution. In this instance a 10-ml sample of the first 100-ml mixture was diluted to 100 ml for the JV absorbance test. Beads O' Bleach contains a triple salt of potassium nonopersulfate.

The data in the Table show that only "Clorox" reacts rapidly.

EXAMPLE 3

Sebum Yellowing Test of Pyrazine Detergent Builders

The sebum yellowing test [Spangler, Cross and Schafama, J. Am. Oil Chemists' Soc., 42, 723 (1965); Chem. Abs. 63, 10179h (1965)] was applied to some pyrazines of Example 1.

Test mixtures of pyrazine detergent builder were prepared with the following approximate composition:

Detergent builder (pyrazine and/or STPP)	35%
Linear tridecylbenzenesulfonate, sodium salt	14%
Sodium silicate, 1/2.35 Na ₂ O/SiO ₂	5%
Sodium sulfate	38%
Water	8%

"Testfabric" (a standard soiled fabric for use in wash tests sold by Testfabric, Inc., New York, N.Y.) is first soiled in a washing machine with heavy duty detergent, containing no brightener or antiredeposition agent, followed by two cycles with "Calgon," a commercial cleaner. It is then rinsed and dried at low temperature. Swatches (3 inches × 5 inches) are soiled with sebum and dried for 0.5 hour at 140°F. Ten soiled swatches (4 cotton, 3 "Dacron" and 3 nylon) are washed in a "Terg-o-Tometer" (a laboratory size dependency test unit sold by U.S. Testing Co. Hoboken, N.J.) in water of predetermined hardness (Ca: Mg = 2.2, expressed as CaCO₃) at pH 10 and containing 0.1% of the test mixture. The "Terg-o-Tometer" cycles are: wash, 0 minutes; rinse, 2 minutes; dry, 1 hour at 230°F. The oiled, washed and dried swatches are spread out overnight and then rated for yellowness (designated as "b" units) determined with a color difference meter (Hunter-Gardner Automatic Model AC-1; Gardner Lab., Inc. Bethesda, Md.). A higher "b" unit reading indicates more yellowness, or less cleaning.

The test results in Table IV below indicate that in this test 2,6-pyrazinedicarboxylic acid, pyrazinetetracarboxylic acid and 1,4,5,6-tetrahydro-5,6-dioxo-2,3-pyrazinedicarbonitrile are close to sodium tripolyphosphate (STPP) in effectiveness as detergent builders.

TABLE IV

Test Mix- ture	TEST RESULTS					
	Pyrazine (%)	STPP (%)	Water Hardness (ppm)	Average Cotton	"b" Unit "Dacron"	Reading Nylon
1a	None	35	150	4.4	9.7	11.9
1b	PDA, 15	20	150	4.9	10.1	13.7

TABLE IV-Continued

Test Mix- ture	TEST RESULTS					
	Pyrazine (%)	STPP (%)	Water Hardness (ppm)	Average Cotton	"b" Unit "Dacron"	Reading Nylon

5d	DPDN, 35	0	250	5.4	10.0	14.9

STPP = sodium tripolyphosphate

PDA = 2,6-pyrazinedicarboxylic acid

PTA = pyrazinetetracarboxylic acid dihydrate

DPDN = 1,4,5,6-tetrahydro-5,6-dioxo-2,3-pyrazinedicarbonitrile

EXAMPLE 4

Sebum Yellowing Test of Pyrazine Detergent Builders

The sebum yellowing test was also used for comparison of pyrazines with sodium tripolyphosphate and sodium citrate in three different detergent systems. The test mixtures in this example contained 33% by weight of builder and the detergent components were as follows:

A. 10/2/2 Formulation	%
Detergent builder	33.0
Linear C ₁₄ -C ₁₅ alcohol ethoxylate (Neodol 45-11)	2.0
Linear tridecylbenzenesulfonate, sodium salt	10.0
Tallow soap, sodium salt	2.0
Sodium silicate solids, 1/2.35 Na ₂ O/SiO ₂	7.5
Sodium sulfate	27.5
Water	18.0
B. LAS Formulation	
Detergent builder	33.0
Linear tridecylbenzenesulfonate, sodium salt	12.0
Sodium silicate solids, 1/2.35 Na ₂ O/SiO ₂	7.5
Water	47.5
C. Nonionic Formulation	
Detergent builder	33.0
Linear C ₁₄ -C ₁₅ alcohol ethoxylate (Neodol 45-11)	12.0
Sodium silicate solids, 1/2.35 Na ₂ O/SiO ₂	7.5
Water	47.5

The test conditions were: 4 inches × 6 inches swatches for cotton, 0.15% concentration of detergent formulation, including builder, in water containing hardness of 150 ppm and adjusted to pH 9.5; 120°F; 10-minute wash, 5-minute rinse, 30-minute drying times.

In this evaluation, overall, the disodium salt of dimethyl 1,4,5,6-tetrahydro-5,6-dioxo-2,3-pyrazinedicarboxylate (SMDPDC) performs as well as sodium tripolyphosphate (STPP) and better than sodium citrate (SCIT). In the non-ionic detergent system C, most of the pyrazines perform as well as STPP.

TABLE V

Builder	Test Results in "b" Unit Values		
	A	B	C
STPP	6.3	6.3	6.1
SCIT	8.1	8.6	6.9

17
TABLE V-Continued

Builder	Test Results in "b" Unit Values		
	A	B	C
MDPDC	7.5	9.0	6.3
SMDPDC	6.2	6.5	4.6
SDPDN	8.8	8.9	5.9
SPDA	10.3	9.9	7.4
SPTA	8.8	8.1	7.6

STPP = sodium tripolyphosphate

SCIT = sodium citrate

MDPDC = dimethyl 1,4,5,6-tetrahydro-5,6-dioxo-2,3-pyrazinedicarboxylate

SMDPDC = disodium salt of MDPDC

SDPDN = disodium salt of 1,4,5,6-tetrahydro-5,6-dioxo-2,3-pyrazinedicarbonitrile

SPDA = disodium salt of 2,6-pyrazinedicarboxylic acid

SPTA = tetrasodium salt of pyrazinetetracarboxylic acid

EXAMPLE 5

Sebum particulate Test of Pyrazine Detergent Builders

The sebum particulate test (Spangler et al., loc. cit.) employs the same general procedure as the sebum yellowing test, but the soiled test fabrics are washed and evaluated for removal of particulate matter as well as sebum. The soiled swatches are first evaluated on a color difference meter (both sides of each swatch) and the average reading (Rd) is noted, the usual average being in the range 55 to 60. After being washed and dried in the test cycle, the swatches are again evaluated on the meter and the average Rd readings noted. The

TABLE VI-Continued

Builder	Test Results in Δ Rd Values		
	A	B	C
SMDPDC	11.4	5.9	18.6
SDPDN	14.1	8.3	19.8
SPDA	9.6	7.5	17.1
SPTA	11.6	10.6	18.3

EXAMPLE 6

Comparative Detergent Performance of
1,4,5,6-Tetrahydro-5,6-dioxo-2,3-pyrazinedicarbonitrile

1,4,5,6-tetrahydro-5,6-dioxo-2,3-pyrazinedicarbonitrile

pyrazinedicarbonitrile was tested as a detergent builder in "Terg-o-Tometer" wash tests involving wash mixtures containing 25 g/liter of "Testfabric" soiled cloth and 3.6 g/liter of test mixture in water of 250 ppm CaCO_3 hardness adjusted to pH 9.4. The test mixtures corresponded to those used in Example 3 and contained 35% builder. The "Terg-o-Tometer" conditions were 120°F., 15 minutes, 125 rpm. The fabrics were evaluated for reflectance increase over starting soiled cloth by means of a "Photovolt" reflectometer with green filter. In this test higher reflectance increase values are measures of increased whiteness and indicate higher performance of the detergent composition, i.e., greater effectiveness in removing and preventing redeposition of soil on the fabric. The results are shown in the following table.

TABLE VII

Test Mix- ture	Detergent Builder	Cotton	Reflectance Increase		
			"Dacron"	"Dacron"/Cotton	"Orlon"
1a	None	9.9	27.1	22.1	25.4
1b	STPP	10.4	22.6	25.3	27.8
1c	NTA	11.8	25.8	25.1	27.5
1d	DPDN	12.2	30.4	25.5	28.1
2a	"Tide" XK	14.2	24.1	25.7	29.2
2b	25/75 DPDN/STPP	12.2	27.9	26.2	27.7
2c	50/50 DPDN/STPP	9.6	27.4	26.2	27.2
2d	75/25 DPDN/STPP	10.9	27.1	22.7	27.2
3a	"Tide" XK	11.7	18.4	27.7	31.0
3b	25/75 DPDN/NTA	7.0	28.4	29.9	29.2
3c	50/50 DPDN/NTA	9.7	27.9	25.7	31.5
3d	75/25 DPDN/NTA	8.5	28.7	28.0	28.5

"Tide" XK = Commercial detergent with brightener and antideposition agent.

STPP = Sodium tripolyphosphate.

NTA = Nitrilotriacetic acid.

DPDN = 1,4,5,6-Tetrahydro-5,6-dioxo-2,3-pyrazinedicarbonitrile.

results of the test are expressed in terms of the differences (Δ Rd) between the before and after readings. The larger the Δ Rd value, the cleaner the washed cloth.

In this example the detergent formulations and test conditions of Example 4 were used. The results indicate that the disodium salt of 1,4,5,6-tetrahydro-5,6-tetrahydro-5,6-dioxo-2,3-pyrazinedicarbonitrile (SDPDN) is the best of the pyrazines in overall performance, being comparable to sodium citrate (SCIT) but less effective than sodium tripolyphosphate (STPP). In the nonionic detergent system C. all of the pyrazines perform about as well as STPP.

TABLE VI

Builder	Test Results in Δ Rd Values		
	A	B	C
STPP	18.5	17.6	19.5
SCIT	14.3	14.1	18.9
MDPDC	12.3	5.9	19.2

EXAMPLE 7

Particulate Soil Test of Pyrazine Detergent Builders

In this test for removal of particulate soil only the general procedure of Example 6 was followed, except that the results are expressed in final Rd values measured with a color difference meter. In addition to controls with sodium tripolyphosphate and sodium citrate, test mixtures containing no builder were also used for comparison purposes. The test mixtures, except in the "no builder" controls, each contained 33% of builder. The final wash solutions contained 1.5 g per liter of formulation in tap water of 150 ppm hardness, were adjusted to pH 9.1, and were used at 120°F wash temperature. The pH of each wash mixture was measured before adjustment to pH 9.1 and again after the wash cycle was completed. Each test involved six swatches of soiled cloth, and duplicate tests were conducted. The detergent components of the test mixtures were as follows:

B. LAS Formulation— Same as B formulation in Example 4.

C. Nonionic Formulation— Same as C formulation in Example 4.

D.	10/2/1 Formulation	%
Linear tridecylbenzenesulfonate, sodium salt	10.0	
Linear C ₁₄ —C ₁₅ alcohol ethoxylate (Neodol 45-11)	2.0	
Tallow soap, sodium salt	1.0	
Sodium silicate, 1/2.35 N ₂ O/SiO ₂	7.5	
Sodium sulfate	28.5	
Water	8.0	

In this test none of the pyrazines matched sodium tri-polyphosphate (STPP) in performance, but dimethyl 1,4,5,6-tetrahydro-5,6-dioxo-2,3-

pyrazinedicarboxylate (MDPDC) and its disodium salt (SMDPDC) were about equal to sodium citrate (SCIT).

TABLE VIII

Builder	Test Results - Rd Values*

fpH = final pH reading.

EXAMPLE 8 Preparation of the Pyrazines

A. 1,4,5,6-Tetrahydro-5,6-dioxo-2,3-pyrazinedicarboxylic Acid Mono Ammonium Salt

A slurry of 0.42 g (2.59 mmole) of 1,4,5,6-tetrahydro-5,6-dioxo-2,3-pyrazinedicarbonitrile in 5 ml of 2N HCl was heated to reflux and a homogeneous amber solution was produced. During additional refluxing overnight, a grey powder was precipitated. The powder, isolated by filtration, washed with acetone on the filter and dried in a vacuum oven at 100°C., weight 0.30 g.

Anal. Calcd for C₆H₇O₆N₃: C, 33.19; H, 3.25; N, 19.35. Found: C, 33.11; H, 3.05; N, 19.05.

B. Dimethyl 1,4,5,6-Tetrahydro-5,6-dioxo-2,3-pyrazinedicarboxylate

A slurry of 7.0 g (32.2 mmole) of the monoammonium salt of 1,4,5,6-tetrahydro-5,6-dioxo-2,3-pyrazinedicarboxylic acid in 100 ml of absolute methanol was cooled in an ice bath as dry hydrogen chloride was passed slowly over the magnetically stirred solution for 3 hours. The heterogeneous mixture was then warmed to room temperature and stirred an additional 3 days. The mixture was filtered, the filtrate was evaporated to dryness, and the filtered solid and residual materials were combined (wt, 6.89 g). The product was recrystallized from methanol and 4.80 g of white needles melting at 250°–252°C was obtained. The purified product was identified as dimethyl 1,4,5,6-tetrahydro-5,6-dioxo-2,3-pyrazinedicarboxylate.

Anal. Calcd for C₈H₈N₂O₆: 42.11; H, 3.53; N, 12.28. Found: C, 41.71; H, 3.65; N, 12.08 41.89. 3.77 12.22 IR (Nujol): 3.08, 3.17, 5.53, 5.67, 5.73, 5.86, 6.67,

60 C. 1,4,5,6-Tetrahydro-5,6-dioxo-2,3-pyrazinedicarboxylic Acid Monosodium Salt Dihydrate

21

A solution of 19.8 g (0.1 mole) of 1,4,5,6-tetrahydro-5,6-dioxo-2,3-pyrazinedicarbonitrile dihydrate and 300 ml of 2N NaOH (0.6 mole) was boiled and sprayed vigorously with nitrogen to remove ammonia. The initial liquid level was periodically maintained by adding water. When no more ammonia could be detected in the off gases, the solution was poured into 200 ml of 6N HCl (1.2 moles). The precipitate was filtered and recrystallized from 500 ml of boiling water (decolorizing hot with a little activated charcoal) to give 21.6 g of 1,4,5,6-tetrahydro-5,6-dioxo-2,3-pyrazinedicarboxylic acid monosodium salt dihydrate with an IR identical with an analytically pure well-characterized sample.

Anal. Calcd for $C_6H_7N_2O_8Na$: C, 29.92; H, 2.73; N, 10.85; Na, 8.90. Found: C, 28.79; H, 2.53; N, 10.95; Na, 8.40.

IR (Nujol): 2.89 and 3.15 82 NH and/or OH, 3.5–4.0 and 5.88 CO_2H , 6.32 and 6.55 H_2O , C=C, and/or CO_2 .

UV $\mu_{max.}^{H_2O} = 297$ nm (ϵ 15,400).

D. 1,4,5,6-Tetrahydro-5,6-dioxo-2,3-pyrazinedicarboxylic Acid

Recrystallization of 2 g of the monosodium salt dihydrate from 102 ml of 6N HCl gave 1.88 g of 1,4,5,6-tetrahydro-5,6-dioxo-2,3-pyrazinedicarboxylic acid dihydrate. This was dried with difficulty for 2.5 days/0.1 mm/111°C to give 1,4,5,6-tetrahydro-5,6-dioxo-2,3-pyrazinedicarboxylic acid [Mager & Behrends, Rec. trav. chim. 77, 842 (1958); Chem. Abs. 53, 10241 (1959)].

Anal. Calcd for $C_6H_4O_6N_2$: C, 36.01; H, 2.01; N, 14.00. Found: C, 35.61; H, 2.05; N, 13.75.

IR: 3340 to 2500 cm^{-1} (broad, OH); 1745 cm^{-1} (C=O); 1685 cm^{-1} (COOH); 1600, 1570 cm^{-1} (C=C/C=N).

UV: $\mu_{max.}^{H_2O} 296$ nm (ϵ 15,600).

HRMS: No molecular ion, $M^+ - H_2O$, meas. m/e 181.9660; calcd for $C_6H_2O_5N_2$, 181.9964.

E. 1,4,5,6-Tetrahydro-5,6-dioxo-2,3-pyrazinedicarboxylic Anhydride

22

A mixture of 65 g of finely ground 1,4,5,6-tetrahydro-5,6-dioxo-2,3-pyrazinedicarboxylic acid, 500 ml of thionyl chloride, and 3.3 ml of dimethylformamide catalyst under nitrogen was cautiously warmed with stirring to reflux and refluxed overnight. The mixture was cooled to room temperature, filtered under nitrogen and dried under a nitrogen stream to give 54.6 g (93.3%) of 1,4,5,6-tetrahydro-5,6-dioxo-2,3-pyrazinedicarboxylic anhydride, a yellow solid, dec. 240°C.

Anal. Calcd for $C_6H_2N_2O_5$: C, 39.57; H, 1.11; N, 15.39; Cl, none. Found: C, 39.41; H, 1.82; N, 15.69; Cl, 3.06. 39.44 1.77 15.16

IR (Nujol) shows strong anhydride absorption at 1780 and 1850 cm^{-1} .

The $SOCl_2$ is used in stoichiometric excess for ease in carrying out the reaction. Dialkylformamides containing from one to six carbon atoms in the alkyl group are useful.

F. Mono(n-dodecyl) Ester of 1,4,5,6-Tetrahydro-5,6-dioxo-2,3-pyrazinedicarboxylic Acid

A mixture of 1 g of 1,4,5,6-tetrahydro-5,6-dioxo-2,3-pyrazinedicarboxylic anhydride and 20 ml n-dodecyl alcohol was heated under nitrogen with stirring at 100°C for 4 hours and filtered hot through a medium sintered glass funnel. The filter was rinsed with hexane and the filtrate diluted with 100 ml of hexane giving a white precipitate which was filtered, rinsed with 100 ml of hexane and air-dried to give 1.38 g of 1,4,5,6-tetrahydro-5,6-dioxo-2,3-pyrazinedicarboxylic acid mono(n-dodecyl) ester. Recrystallization of 1.33 g from 20 ml of benzene gave 0.85 g of white solid, mp, 162.8°–164.6°C.

Anal. Calcd for $C_{18}H_{28}N_2O_6$: C, 58.68; H, 7.66; N, 7.60. Found: C, 58.89; H, 7.74; N, 7.33. 59.13 7.81 7.43.

UV: $\lambda_{max.}^{dioxane}$ 294 nm (ϵ 11,700)

IR (Nujol): OH/NH at 3150–3400 cm^{-1} , $-CO_2H$ at 2550 (broad), ester at 1770, C=O at 1710, 1650.

NMR (DMSO-d₆): broad peak at δ 9.85 (2.64 H, CO_2H , NH), ca. triplet 4.10 (1.72 H, 13 OCH_2-), and singlet 1.15 [–(CH₂)₁₀–] and triplet 0.75 (–CH₃) of area 23.05.

Mass spectrum (trimethylsilylated): strong m/e 584 for tris(trimethylsilylated) parent ion.

When an excess of saturated aqueous sodium carbonate was added to the mono-ester in water, in the solid ester partially dissolved, forming a hazy solution indicative of micelle formation. When this was shaken a foam (suds) formed which was stable for at least 0.5 hour. 5 These properties were similar at 25° and 60°C. and were quenched by calcium acetate.

G. Mono-“Carbitol” Ester of 1,4,5,6-Tetrahydro-5,6-dioxo-2,3-pyrazinedicarboxylic Acid Monosodium Salt

a mixture of 15.09 g of 1,4,5,6-tetrahydro-5,6-dioxo-2,3-pyrazinedicarboxylic anhydride and 300 ml of “Carbitol” was heated under nitrogen with stirring at 100°C for 4 hours. After standing 4 days at 25°C, the mixture was diluted with 1.5 liters of dioxane, stirred for 2 hours and filtered to remove 2.24 g of insoluble white solid impurity. The filtrate was treated with 82.5 ml of 1.00N NaOH, precipitating a white solid which was filtered, rinsed with dioxane, and dried overnight over P_2O_5 at 25°C/0.02 mm to give 20.2 g of mono-“Carbitol” ester of 1,4,5,6-tetrahydro-5,6-dioxo-2,3-pyrazinedicarboxylic acid monosodium salt.

Anal. Calcd for $\text{C}_{12}\text{H}_{15}\text{N}_2\text{O}_8\text{Na}$: C, 42.61; H, 4.47; N, 8.28; Na, 6.79. Found: C, 41.25; H, 4.37; N, 7.88; Na, 7.30.

IR (Nujol): quite sharp overall, broad OH/NH 2600-3300 cm^{-1} , strong sharp C = O, X = Y at 1630, 1680, 1725. Lack of absorption between 50 1500 and 1630 probably rules out CO_2Na .

The usual titration with calcium acetate of a pH 11.5 solution of this product containing added Na_2CO_3 did not reach an endpoint until extra Na_2CO_3 was added. The apparent, but probably not actual, calcium chelating activity was greater than 5 g of CaCO_3 chelated/gram of product.

H. Di(n-dodecyl) 1,4,5,6-tetrahydro-5,6-dioxo-2,3-pyrazinedicarboxylate

- 10 A mixture of 1.00 g of 1,4,5,6-tetrahydro-5,6-dioxo-2,3-pyrazinedicarboxylic anhydride and 20 ml of n-dodecyl alcohol was heated with stirring under nitrogen at 100°C. for 2 hours. Then 0.2 ml of concentrated sulfuric acid catalyst was added and the heating continued for another 5 hours. The mixture was filtered hot and the solid on the filter was rinsed with n-dodecyl alcohol. The product was precipitated from the filtrate with n-hexane to give 1.65 g of white solid, di-(n-dodecyl) 1,4,5,6-tetrahydro-5,6-dioxo-2,3-pyrazinedicarboxylate. This was recrystallized from 200 ml of n-hexane/60 ml benzene to give 1.63 g, mp, 145.8°-146.3°C. Its solubility is low in benzene, hexane, and diluted NaOH.
- 15 Anal. Calcd for $\text{C}_{30}\text{H}_{52}\text{O}_6\text{N}_2$: C, 67.13; H, 9.77; N, 5.22. Found: C, 67.50; H, 9.76; N, 5.07.
- 20 UV: $\lambda_{max}^{dioxane}$ 294 nm (ϵ 13,500).
- 25 IR (KBr): no $-\text{CO}_2\text{H}$, has ester 5.72 μ .
- 30 NMR (CDCl_3): broad peak δ 10.0 ppm (1.9H, NH), triplet at 4.35 (4.0 H, $-\text{OCH}_2-$), ca. singlet 1.30 and ca. triplet 0.90 (47.0 H, $(\text{CH}_2)_{10}$ and CH_3).

Mass spectrum: intense m/e 536 parent ion, 324 ($\text{M}-\text{CO}_2\text{C}_{12}\text{H}_{25}$)⁺, 323, 201, 183.

When the n-dodecyl alcohol above is replaced by a higher alcohol such as that corresponding to the formula $\text{HO}(\text{CH}_2\text{CH}_2\text{O})_{23}\text{C}_2\text{H}_5$ the resulting pyrazine is di(3,6,9,12,15, 18,21,24,27,30,33,36,39,42,45,48,51,-54,57,60,63,66,69-tricosaoxahenheptacont-1-yl) 1,4,-5,6-tetrahydro-5,6-dioxo-2,3-pyrazinedicarboxylate of the formula

I. 3,5-Bis(methoxycarbonyl)-2,6-pyrazinedicarboxylic Acid and 3,6-Bis(methoxycarbonyl)-2,5-pyrazinedicarboxylic Acid.

Pyrazinetetracarboxylic dianhydride¹ (115.1 g, 0.525 mole) was dissolved in 1,000 ml of absolute methanol under nitrogen. After 2 hours the solution was treated with a small amount of "Darco", filtered, concentrated to a slush, and filtered. The filtered solid was partially dried, rinsed with carbon tetrachloride and dried. The dried product (67.2 g) was an approximately 90/10 mixture of 3,6-bis (methoxycarbonyl)-2,5-pyrazinedicarboxylic acid/3,5-bis (methoxycarbonyl)-2,6-pyrazinedicarboxylic acid. Pure 3,6-isomer, mp., 210°-211°C. (dec.), was isolated from this mixture by recrystallization from methanol.

¹ Pyrazinetetracarboxylic dianhydride is described in Chem. Abs. 71, 124488a (1969).

Anal. Calcd for $C_{10}H_8N_2O_8$: C, 42.26; H, 2.84; N, 9.89. Found: C, 41.16; H, 2.71; N, 9.36 41.22 2.79

9.51.

UV (ethanol); μ max. 280 nm (K 28.2) and 320 nm (K 2.2).

IR (Nujol): 947, 738 and 722 cm^{-1}

The residue from the recrystallization filtrate was a mixture containing the 3,5- and 3,6-isomers in a ratio of about 7:3. Infrared analysis of the mixture showed absorption at 1025, 929, 757 and 704 cm^{-1} , which is not shown by the pure 3,6-isomer.

EXAMPLE 9

Salts of 2,3-Dihydroxy-5,6-pyrazinedicarbonitrile from 35 1,4,5,6-Tetrahydro-5,6-dioxo-2,3-pyrazinedicarbonitrile

1,4,5,6-Tetrahydro-5,6-dioxo-2,3-pyrazinedicarbonitrile is tautomeric with 2,3-dihydroxy-5,6-pyrazinedicarbonitrile but in the absence of a base exists almost entirely in the dioxo form, as indicated by its strong IR carbonyl absorption. In the presence of a base it readily forms a dianion with low carbonyl IR absorption and can form stable salts.

A. Ammonium Salt

A solution of 5.0 g of 1,4,5,6-tetrahydro-5,6-dioxo-2,3-pyrazinedicarbonitrile in 100 ml of anhydrous ammonia was stirred for 2 hours at -35°C. and then warmed to room temperature. A tan solid (5.1 g) remained after evaporation of the ammonia. Pure diammonium salt of 2,3-dihydroxy-5,6-pyrazinedicarbonitrile was obtained in the form of light

yellow needles, mp, 230°C (dec), by recrystallization of the crude salt from water.

Anal. Calcd for $C_6H_8N_6O_2$: C, 36.73; H, 4.11; N, 42.84. Found: C, 36.37 H, 4.03; N, 40.00.

5 IR: No carbonyl absorption. Strong absorption for CN, NH and/or OH, and aromatic double bonds.

B. Sodium Salt

The disodium salt of 2,3-dihydroxy-5,6-pyrazinedicarbonitrile is readily formed by mixing 10 aqueous solutions of the dioxo compound and sodium hydroxide in 1:2 molar ratio. The salt solution has a pH 7 and gives dry solid when the water is stripped away by evaporation. Alternatively, the salt can be prepared from the oxo compound and sodium cyanide in acetonitrile containing about 20% of dissolved hydrogen cyanide, the salt being isolated by evaporation of the solvent and HCN. The salt can be recrystallized from water. Infrared analysis shows strong absorption by conjugated cyano and multiple NH and/or OH groups. Acidification of an aqueous solution and extraction with ether yields 1,4,5,6-tetrahydro-5,6-dioxo-2,3-pyrazinedicarbonitrile from the extract.

C. Calcium Salt

A mixture of 8.11 g (50 mmoles) of 1,4,5,6-tetrahydro-5,6-dioxo-2,3-pyrazinedicarbonitrile, 8.81 g (50 mmoles) of calcium acetate monohydrate and 50 ml of water was refluxed for 1 hour, cooled to 0°C. and filtered. The filtered white solid (9.70 g, 82.2%) was the dihydrate of the calcium salt of 2,3-dihydroxy-5,6-pyrazinedicarbonitrile. The filtrate yielded 1.84 g (15.6%) of the same product.

Anal. Calcd for $C_6O_2N_4Ca \cdot 2H_2O$: C, 30.50; H, 1.71; N, 23.70; Ca, 16.97. Found: C, 30.86; H, 1.66; N, 23.83; Ca, 19.01 19.06.

The calcium salt dihydrate was also obtained in 87% yield of filtered solid by carrying out the above procedure with sodium hydroxide present in an amount equivalent to the calcium acetate.

Other salts can be made in analogous manner.

40 The embodiments of the invention in which an exclusive property or privilege is claimed are defined as follows:

1. A compound of the formula

55 wherein R^4 and R^5 , alike or different, are selected from the group OH, alkoxy, oxaalkoxy, (alkylphenyl)oxaalkoxy each of 1-48 carbon atoms, and, together, are -O-, with the proviso that only one of R^4 and R^5 can be OH; and with the further proviso that when R^4 and R^5 are both alkoxy groups, each alkoxy group contains 4-48 carbon atoms; and

60 b. water soluble alkali metal salts thereof.

2. The compound of claim 1 in which R^4 is ethoxy and R^5 is OH; monoethyl ester of 1,4,5,6-tetrahydro-5,6-dioxo-2,3-pyrazinedicarboxylic acid.

65 3. The compound of claim 1 in which R^4 is $O(CH_2C_2H_5)_2$ and R^5 is OH; mono [2-(2-ethoxyethoxy)ethyl] ester of 1,4,5,6-tetrahydro-5,6-dioxo-2,3-pyrazinedicarboxylic acid.

27

4. The monosodium salt of the compound of claim 3.
 5. The disodium salt of the compound of claim 3.
 6. The compound of claim 1 in which R⁴ is O(CH₂C-H₂O)_nCH₃, where n = 7.2 average, and R⁵ is OH; mono(monomethyl ether of polyoxyethylene) ester of 1,4,5,6-tetrahydro-5,6-dioxo-2,3-pyrazinedicarboxylic acid.
 7. The compound of claim 1 in which R⁴ is n-butoxy and R⁵ is OH; mono(n-butyl) ester of 1,4,5,6-

- tetrahydro-5,6-dioxo-2,3-pyrazinedicarboxylic acid.
 8. The compound of claim 1 in which R⁴ and R⁵ together are —O—; 1,4,5,6-tetrahydro-5,6-dioxo-2,3-pyrazinedicarboxylic anhydride.
 9. The compound of claim 1 in which R⁴ and R⁵ are each n-dodecyloxy; di(n-dodecyl) 1,4,5,6-tetrahydro-5,6-dioxo-2,3-pyrazinedicarboxylate.
